PRINTING MACHINE

Walter T. Gollwitzer, Cleveland, Ohio, assignor,
by mesne assignments, to Addresograph-
Multigraph Corporation, Cleveland, Ohio, a
corporation of Delaware

Application July 8, 1931, Serial No. 549,347
Renewed July 29, 1935

42 Claims. (Cl. 101—58)

This invention relates to printing machines of the kind wherein impressions are made on sheets successively passed therethrough.

In machines of this kind the sheets are sometimes severed from a web to be passed through the machine and a permanent form is printed thereon in the machine. Sometimes the permanent form is printed on the sheets prior to introduction thereof into the machine. As the sheets move through the machine other impressions, usually in the nature of names and addresses, are made thereon from changeable printing devices sequentially passed through the machine. Usually impressions are made on each sheet from a changeable printing device, and, when the sheets are sectional, impressions are made from the printing device onto each section of the sheet. Sheets of this nature are used as bills by gas, electric and telephone companies and the like, and they are also used as notices or for other purposes by insurance companies and the like. In addition to the permanent form and the data adapted to be printed on the sheets from the changeable printing devices, other variable data is often printed thereon, as, for example, quantities, prices and extensions thereof and the like. This variable data is related to data adapted to be printed from the changeable printing devices.

An important object of my invention is to provide a novel printing machine wherein data may be printed from changeable printing devices and wherein other variable data, related to the data printed from the changeable printing devices, may also be printed onto sheets passed through the machine.

A further important object of the invention is to provide an apparatus to identify individual elements of one set of devices with individual elements of another set, supposed or intended to correspond therewith, and particularly to effect such identification during a useful operation on or in connection with the elements of one set by appropriate mechanism.

Other objects include the provision of a machine arranged to compare relates devices, such as sets of control cards and printing devices each supposedly arranged in a predetermined order and respectively provided with identifying indicia, so that the machine, or parts thereof, will function in accordance with whether or not the indicia of supposedly related devices at respective stations of such devices correspond.

Another object is to provide a printing machine wherein the printing of variable data may be

determined by control devices so passed through the machine that the relation between the variable data and the data adapted to be printed from changeable printing devices may be maintained.

Sometimes the variable data is arranged in groups and a further object is to individually print the data of the various groups and to move the sheet into positions whereat this individual printing may be performed.

Other objects are to provide a mutable or settable printing mechanism to print variable data; to so position the sheets that the impressions will be made thereon at predetermined places; to operate the various parts of the machine in definite timed relation; to effect a signal, as by interrupting the operation of the machine in the event of improper operating conditions; and to provide a machine which will be efficient and positive in operation and simple in construction.

General arrangement (sheet feed and driving mechanism)

10 In the selected embodiment of the invention illustrated in the accompanying drawings, I have shown a novel printing machine of the kind wherein impressions are made from changeable printing devices onto sheets moved through the 15 machine. This printing machine may be, for example, one of the kind disclosed in my copending application, Serial No. 497,438, filed November 22nd, 1930 (now Patent No. 2,002,772, issued May 28th, 1935), and it includes a table 18 on 20 which impressions are made onto the sheets S stored in a rack T mounted at one end of the machine frame 17. The sheets stored in the rack T are cut to size and have a permanent form printed thereon.

25 Alternatively, the invention may be used with a printing machine of the kind disclosed in the application of Emmett C. Hartley, Serial No. 459,-599, filed June 6th, 1930, wherein the permanent form is printed on sheets that are severed from 30 a web withdrawn from a roll of paper.

The sheets severed from the web, or withdrawn from the rack T in the manner disclosed in my copending application, Serial No. 497,440, filed November 22nd, 1930 (now Patent No. 2,002,773, 35 issued May 28th, 1935), are moved onto endless conveyor belts 26, directed about pulleys 27 and 28 mounted at opposite ends of the table 18 and also around guiding pulleys such as 29 carried by the brackets 30 on the frame 17, to be moved 40 through the machine whereby impressions may be made thereon from the changeable printing devices and the mutable printing mechanism.

The disclosed machine includes a drive shaft 19 journaled in the frame 17 and having a fly-wheel driving pulley 20 rotatably mounted thereon. A clutch controlled by the lever 21 is used to connect the pulley 20 to the shaft 19 to thereby transmit power supplied to the pulley, from a suitable source, to the shaft 19. On the shaft 19 there is a bevel gear 22 meshing with a bevel gear 23 fast on the platen operating shaft 24 which extends across the machine and which acts through a suitable mechanism to operate the platen P. A cam shaft 25 is provided and this cam shaft and the conveyor belts 26 are driven from the shaft 19 in the manner described in my Patent 2,002,772, above mentioned.

60 The cam shaft 25 operates stop fingers F' which engage the sheets S carried by the belts 26 to orient the sheets in position below the platen P whereby said platen may make impressions thereon through the usual ink ribbon from the changeable printing devices which are moved into printing position relative to the platen.

65 *Changeable printing devices; feed therefor*

The changeable printing devices, which may be arranged as individual address printing members, (example at D, Figs. 2, 9, and 15), are introduced into a magazine M in a predetermined sequence and are withdrawn from the magazine and passed through printing position in a step-by-step manner, and when sectional sheets are being printed the printing devices are retained in printing position until an impression has been

made therefrom onto each section of the sheet receiving impressions from this printing device. A typical means for withdrawing such printing devices and for retaining them in printing position is disclosed in my copending application, Serial No. 497,438, filed November 22nd, 1930, (now Patent 2,002,771, issued May 28th, 1935).

Example of work printed

The sheet S is illustrated in detail in Fig. 16 10 and embodies three sections onto each of which sections an impression R is made from a printing device D, the impression R consisting, for example, of a name and address and other pertinent data. A typical changeable printing device D is illustrated in Fig. 9, and consists of a frame 35 having a printing plate 36 and a card 37 on one face thereof. The printing plate is embossed to provide the printing characters for making the impression R, and it should be noted that in addition to the type characters for the impression R the printing plate has characters embossed thereon which represent an account number N. This account number is printed onto 20 the sheet at a predetermined place as, for example, in the middle section on the sheet S shown in Fig. 16.

In order that the account number N will be printed on the sheet only at selected places, the 30 platen P is provided with a portion which may be receded and the number N will only be printed when the portions of both sections of the platen are aligned. One form of receding platen and means for controlling the same are illustrated in 35 my Patent 2,002,772, and this form may be used herein, the cam shaft 25 carrying, when this form of receding platen is used, a suitable cam for controlling the platen.

The platen shaft 24 makes one complete revolution 40 for each section of the sheet to be printed but the cam shaft 25 makes but one revolution during the printing of a sheet, this ratio of operation between these shafts being determined by suitable gearing.

Mutable printing mechanism

The conveyor belts 26 move the sheet into a mutable printing mechanism wherein variable data is printed on the sheet after the sheet has 50 been properly printed by the platen P. The mutable printing mechanism is adapted to print data related to the impressions made from the changeable printing devices.

55 *Control and identification devices*

The operation of the mutable printing mechanism is determined by the conjoint action of main control devices and cooperating control devices, 60 the latter being carried on the changeable printing devices.

The main control devices C, Fig. 1a, are introduced into a magazine A in the same sequence as the sequence of the printing devices introduced into the magazine M, and each of the printing devices has a cooperating control device (example at 37, Fig. 15), whereby each sheet will receive impressions from a changeable printing device and from the mutable printing mechanism 70 which will be arranged, through the medium of the control device C, e. g. related to the printing device from which the impressions were made, to print data related to that printed from the changeable printing device.

Control device C

The control device C may be in the nature of a card of a non-conductive material and has a lineation thereon with which suitable identifying indicia is associated. The control device is perforated at predetermined places in the lineation relative to the indicia and means cooperating with these perforations determine the functioning of the printing mechanism.

In Fig. 1a it may be seen that associated with a portion of the lineation is the indicia, "Street number" and "House number". The perforations made in the lineation relative to this indicia designate the account number of the control device and the account number on the control device is the same as the account number on the printing device to which the particular control device is related; as for example, the printing device D illustrated in Fig. 9 bears the account number "720-1260" and the control device C illustrated in Fig. 1a is perforated in association with the indicia, "Street number" and "House number" to have the same account number.

The control device C having said account number is used to set up the mutable printing mechanism to print the variable data on the sheet which received impressions from the changeable printing device bearing the corresponding account number, which account number, incidentally, is imprinted on the sheet by the receding portion of the platen P.

Identification of control and changeable printing devices

To ascertain whether or not the sequence of the control devices corresponds to the sequence of the changeable printing devices so that the interrelation thereof will be insured, a detecting means, now to be described, and acting on indicia of both the control devices and printing devices, is provided in the machine.

The printing devices D are withdrawn from the magazine M and are passed through four stages, W, X, Y, and Z, (Fig. 2), the stage Z being printing position in the machine while the stage W is the one immediately in front of the magazine M. Since the machine is provided with four stages for the printing devices D, it is necessary to provide four stages for the control devices. The stages W, X, Y, and Z for the printing devices are provided in the printing device guideway and the corresponding stages for the control devices, indicated by W', X', Y', and Z', (Fig. 5) are provided about the periphery of a drum 34.

Feeding of control devices C (drive, etc.)

A slide 31 is mounted for reciprocation below the magazine A and includes a shoulder 32 of slightly less height than the thickness of one of the control devices. Reciprocating movement is imparted to this slide, and when it is moved toward the left, as viewed in Fig. 4, a control device is moved from the magazine A into a pocket 33 (Figs. 4 and 5) in the periphery of the drum 34, located at the stage W'. The control device thus moved into the stage W' should bear an account number e. g. corresponding to the account number e. g. on the printing device in the stage W, and detecting means act on these devices to determine whether or not the account numbers e. g. do correspond.

If the account number on the control device C should differ from the account number on the printing device, operation of the illustrated ma-

chine is interrupted to permit the operator to ascertain the reason for the discrepancy and to permit correction.

The mutable printing mechanism and the drum 34 are operated from a source of power independent of that operating the platen P and allied mechanisms, and this independent source of power includes a motor 38 (Fig. 3) mounted at the rear of the machine and adapted to be connected to a shaft 39 (Fig. 8) through a jaw clutch 40. On the shaft 39 there is a worm gear 41 meshing with a worm wheel 42 fast on the shaft 43 journalled in bearings 44 (Fig. 3) provided in the frame of the machine. Fast on the shaft 43 is a miter gear 45 (Fig. 2) meshing with a miter gear 46 fast on the shaft 47 journalled in bearings 48 carried by the frame of the machine. The drum 34 is fast on a shaft 49 journalled in bearings 48' and secured to this shaft at one end of the drum is a circular ratchet 50 (Figs. 4 and 6). Mounted for movement about the shaft 49 is a rocker 51 carrying a pawl 52 yielding urged, by a spring 53, into engagement with the teeth of the ratchet 50. One end of a link 54 (Fig. 4) is pivotally mounted between two crank discs 55 (Figs. 4 and 6) fast to adjacent ends of independent sections of shaft 47. The discs are connected by the crank pin 56 on which the link 54 is pivoted. The crank discs 55 rotate with the shaft 47 and impart a reciprocatory movement to the link 54 to pivot rocker 51 about shaft 49 whereby pawl 52 will successively engage teeth in the ratchet 50, said pawl seating in one of said teeth to move said ratchet during counterclockwise movement of the rocker 51, as viewed in Fig. 4, and freely riding on the periphery of the ratchet during clockwise movement of said rocker.

Thus, a step-by-step movement is imparted to the drum shaft 49 and drum 34 and in this manner the pockets 33 in the periphery of the drum are successively moved through the stages W', X', Y', and Z'. The frame of the machine extends between one end of the drum and the ratchet 50. Pivotally mounted at 51' (Fig. 4) on this frame is a pawl 52', urged into engagement with the teeth of the ratchet 50 by a spring 53', and this pawl 52' prevents retroactive movement of the ratchet and the drum.

The slide 31 is synchronically operated with the drum 34 from a rocker 57 (Figs. 4 and 5) pivotally mounted on shaft 58 carried by the frame. On arm 59 of this rocker is a roller 60 riding on the peripheral cam 61 fast on shaft 47. Links 63 are pivotally connected to arms 62 on rocker 57 and to ears 64 depending from the slide 31. The slide 31 and the drum 34 are so timed that the leading edge of a control device moved by the slide 31 will engage the leading end of a pocket 33, these pockets being defined between adjacent sets of spaced abutments 65 (Fig. 13).

At a tangential point on the drum 34, in substantial horizontal alignment with the line of movement of the control device, as caused by the slide 31, a plurality of rollers 66 are mounted on a shaft 66'. The rollers are spaced along the shaft so that the abutments 65 may pass therebetween. Immediately after the leading edge of a control device engages the abutments 65 at the leading end of a pocket 33, the control device is clamped onto the periphery of the drum 34 by the rollers 66 and will thereafter move with said drum, as a drop on the cam 61 will at this time permit the spring 67 (Fig. 5) to retract the slide 31. The control device will move with the drum 34 until it is in a position substantially similar

to that shown in Fig. 5, whereat the parts come to rest.

Detecting (control and printing device comparison)

5 On the next cycle of operation of the machine, suitable detecting means act on the control device so moved from the magazine A to W', and the printing device in the stage W to ascertain 10 whether or not the indicia on the respective devices correspond. The detecting means cooperating with the control device just moved from the magazine into the stage W' comprise an insulating block 68 (Fig. 5), carrying a plurality of 15 brushes 69 aligned with that portion of the control device bearing the perforations for the account number. When the drum 34 starts to move, as caused by counter-clockwise operation of the rocker 51, as viewed in Fig. 4, the control device 20 in the stage W' will pass below the brushes 69 into the stage X'. At this same time, (see Figs. 10 to 12), detecting means cooperating with indicia associated with the printing device in the stage W will move over the card 37 on the printing device, which, in the example shown, bears 25 the printing device indicia.

Detecting means of printing devices

30 A lineation is provided on the card 37 corresponding to the lineation associated with the indicia "Street number" and "House number" on the control device. The perforations will be provided in this lineation corresponding to the account number on the printing device, and the 35 detecting means at the stage W cooperates with these perforations as it traverses the card 37.

The detecting means at the stage W includes 40 an insulating block 10 (Figs. 10 to 12, inclusive) carrying a plurality of brushes 71. The "at rest" 45 position of the detecting means including the block 10 is illustrated in Fig. 10 and the parts are in this position at the time the drum 34 is in its at rest position, and the detecting means and the drum are moved in synchronism from their at 50 rest positions. The block 10 is carried by an arm 72 pivotally mounted on a frame 73 slidable on rods 74 carried by the frame of the machine. One end of a link 75 (Fig. 2) is connected to the frame 73 and a rack 76 is provided at the other 55 end of the link and meshes with a gear segment 77 (Fig. 4) that is part of the rocker 51, a guide 60 being provided to insure proper movement of the rack 76.

The pitch line of the gear segment 77 is aligned 55 with the periphery of the drum 34 and therefore the speed of movement of the rack will be synchronic with the circumferential speed of the drum 34. Thus, as the rocker 51 moves, the drum 34 and the rack 76 and link 75 will move in synchronism and consequently the control device 60 will move from the stage W' into the stage X' past the brushes 69 in synchronism with the movement of the brushes 71 across the card 37 on the printing device in the stage W, this movement 65 of the brushes 71 taking place during the counter-clockwise movement of the rocker 51. When this rocker moves in a clockwise direction, the brushes 71 are lifted clear of the card 37 and latched in this position. A latch 79 on the frame 70 73 is urged downwardly by a spring 80, the action of the spring being limited by engagement of the latch 79 with an arm 81 unitary with the arm 72. The arm 72 carrying the insulating block 10 engages an adjustable screw 82 carried by the 75 frame of the machine just prior to movement

thereof into the position illustrated in Fig. 10. When the arm 72 engages the screw 82, the latch 79 latches the arm 81 and the brushes 71 are held in an elevated position whereby as the parts move into the position illustrated in Fig. 12, the 5 brushes 71 will be held clear of the card 37 and, as the frame 73 approaches the position illustrated in Fig. 12, the tail 83 on the latch 79 engages the adjusting screw 84 to pivot the latch 79 from engagement with the arm 81 to thus release the brushes 71 so that when the frame 73 is again moved toward the position illustrated in Fig. 10, these brushes will be in position to traverse the card 37.

15

Detector circuit (and electrical apparatus)

In Fig. 15 it is shown that conductors 85 separately extend between the respective brushes 69 and 71 and that the winding 86 (Fig. 6) of a relay 20 is connected in each of these conductors. The printing device D in the stage W is completely insulated from the frame of the machine and mounted therebelow is a contact plate 87 (Fig. 12) to which a conductor 88 is connected, and this 25 conductor is connected to one line of a source of electric current. The drum 34 is made of insulating material and at the bottom of each of the pockets 33 there is a conductive contact plate 89. As best illustrated in Figs. 5 and 14, a spring contact 90 is mounted on the frame at one end of the drum 34 to be engageable with the contact plates 89 in the stage W'. The contact 90 is carried by and insulated from the frame of the machine. A conductor 91 connects the conductor 90 to the 30 other line of the source of electric current.

As the control devices C move past the brushes 69 and as the brushes 71 synchronically move over the card 37 and if the control device and card are similarly perforated, the brushes will 40 simultaneously pass through perforations in the control device and card. Whenever a brush 69 and a corresponding brush 71 move through perforations, a circuit will be closed to the relay 86 in the conductor 85 interconnecting the corresponding brushes, the control devices and cards 37 being of insulating material and therefore preventing the closing of the circuit until the brushes pass through openings.

Referring to Fig. 6, each relay 86 includes an 50 armature 92, pivotally mounted in the frame 93 carried by the frame of the machine. Each armature includes a depending leg 94 of insulating material carrying an adjustable screw 95 having a conductor 96 connected thereto. Whenever the armature 92 of a relay is in its unattracted position, shown in Fig. 6, the screw 95 engages a spring contact 97 having conductor 98 connected thereto. When, however, a relay 86 is energized the armature 92 thereof is attracted 60 and latched in the pawl 99, normally urged toward the armature by the spring 100. When an armature is so attracted the circuit between the screw 95 and the contact 97 associated therewith is opened.

Referring now to the electrical diagram, Fig. 15, each of the conductors 85 is shown as connected to a conductor 101, and each of the conductors 88 to a conductor 102. The conductor 101 is connected to one terminal of a suitable source of 70 current. The conductor 102 is connected to one end of the winding of an electro-magnet 103. A conductor 104 is connected to the other end of the winding of the electro-magnet and to the other terminal of the source of current.

65

75

Timing switch and relay operation

In the conductor 101 is a timing switch 105 (Figs. 6 and 15), which is controlled by a cam on the cam shaft 25. The armature 106 of the electro-magnet 103 is connected to the clutch control lever 21 (Figs. 1 and 15). When the control device C passing below the brushes 69 is perforated to correspond to the card 37 traversed by the brushes 11, all of the relays 86 will be energized and each of the armatures 92 will be attracted and consequently each of the screws 95 will be disconnected from the spring contacts 97 and therefore circuit between the conductors 101 and 102 will be opened. Thus, when the cam shaft 25 operates to close the timing switch 105, the electro-magnet 103 will not be energized and the armature 106 thereof will not move the arm 21 to disconnect the clutch. However, should either or both of corresponding brushes 69 and 11 fail to simultaneously move through perforations, circuit to the relay 86 in the conductor 85 connecting these corresponding brushes will not be closed and consequently the armature 92 thereof will not be attracted and therefore the contacts 95 and 97 will not be separated and circuit between the conductors 101 and 102 will be closed.

From the above it is apparent that when the timing switch 105 is closed, the electro-magnet 103, Figs. 1 and 15, will be energized and the armature 106 will be attracted and the lever 21 will be operated and consequently the clutch controlled thereby will disconnect the pulley 20 from the shaft 19 and operation of the machine will be interrupted. Manifestly, this will occur when the account numbers on the control and printing devices do not correspond and since operation of the machine will be interrupted the operator will thus be signalled and may ascertain the nature of the discrepancy between the control and printing devices and may make the necessary correction.

It is within the purview of my invention to provide suitable indicating means which may be operated from the relays 86 to inform the operator precisely where the discrepancy occurred to facilitate location of the trouble.

Summary of comparison

The foregoing detecting operation is performed on each of the printing devices D moving into the stage W and each of the control devices C moving into the stage W' and therefore operative similarity between these devices may be insured so that the corresponding devices will move through the machine in definite relation to each other. It follows that the impressions from the mutable printing mechanism will be made onto sheets receiving impressions from the changeable printing device corresponding to the control device determining the set-up of the mutable printing mechanism.

Mutable printing mechanism control

As the control device C moves from the stage W' into the stage X' it passes below a set of rollers 67' which are spaced similarly to the spacing of the rollers 66 to permit the abutments 65 to pass therebetween. The rollers 67' serve to retain the control device in the stage X' on the periphery of the drum and at spaced intervals about the periphery of the drum there are other sets of rollers 68' which are similar to the rollers 67' and 66, and these sets of rollers serve to retain the control devices in the pockets on the drum 34 as these control devices are moved in a

step-by-step manner with the drum into the various stages. The various sets of rollers, spaced about the periphery of the drum between the tangential position whereat the control device moved by the slide 31 engages the drum and discharge position, have pinions (Figs. 4 and 13) fast on the shafts carrying said rollers. These pinions mesh with a gear 70' fast to one end of the drum 34. The shafts for these rollers are carried in slots in the machine frame and springs 11' (Fig. 4) act on these shafts to urge the rollers toward the periphery of the drum whereby the control devices will be securely clamped in position, suitable adjustments being provided by varying the tensions of said springs.

The movement of the control devices past the brushes 69 does not affect the mutable printing mechanism as these brushes merely serve to determine whether or not the control device corresponds to the printing device to which it is related. It has been stated, however, that an object of the invention is to print variable data on the sheets related to the impressions made on the sheets from the changeable printing devices.

Typical work

In Fig. 16, wherein a typical sheet to be printed is illustrated, the variable data is printed in two rows J and K which extend longitudinally across the sheet S. In the embodiment of the invention selected for illustration in the accompanying drawings, all of the data in the row J is printed in one operation and all the data printed in the row K is printed in another operation. The illustrated sheet has two rows of data thereon, but it is to be understood that additional rows might be desired and in such circumstances additional mutable printing mechanism would be provided.

Duplex character of mutable printing mechanism

In the illustrated embodiment of the invention, the impressions in the row J are printed in a printing couple E (Fig. 1) and the impressions in the row K are printed on the sheet in a printing couple F (Fig. 1) disposed in the machine in horizontal alignment with the printing couple E. If additional rows were to be printed, additional printing couples would be provided. Each of these printing couples includes mutable printing devices controlled by the control devices C. In addition to the mutable printing devices, each of these printing couples includes a platen P' which makes impressions onto the sheets through a suitable ink ribbon, it of course being understood that inking means other than an ink ribbon might be employed without departing from the ambit of my invention.

Platen operation (mutable printing mechanism)

The platen P' for the printing couple E has two sections 107 and 108 which are independently mounted to facilitate adjustment thereof to insure that uniform impressions will be made thereby. The platen sections 107 and 108 are mounted on a rocker 109 which embodies arms 110 (Fig. 6) pivotally mounted on the frame of the machine. Springs 111 act on the rocker arms 110 to urge the rocker into an upper position to support the platen P' in spaced relation with the printing devices with which it cooperates. A roller 112 on each of the arms 110 is engageable with a cooperating cam 113 fast on the shaft 114 journalled in the frame of the machine and

having a gear 115 thereon meshing with a gear 116 on the platen operating shaft 24. The ratio between these gears corresponds to the number of sections on the sheets to be printed and in the present instance the ratio is three to one so that the shaft 114 will make but one complete revolution while the platen operating shaft 24 is making three complete revolutions, and therefore the platen P' will be operated but once while the platen P is operated three times. A rise 117 (Fig. 6) on each of the cams 113 engages the roller 112 cooperating therewith to force the arms 110 downwardly to cause the platen to descend to perform a printing operation.

15   *Character selection (printing couple E)*

The printing devices in the printing couple E consist of a plurality of elongated type bars 118 (Fig. 14) having the integers zero to nine aligned 20 on the upper face thereof, these integers being in the form of type characters. These type bars are positioned substantially side-by-side longitudinally of the machine in position so that impressions will be made therefrom at desired places 25 on the sheet positioned relative thereto by the engagement of the leading edge of the sheet, which will be carried by the conveyor belts 28, and positioned by one of a series of stop fingers F' operated by the cam shaft 25. Castings 119 and 120 (Fig. 6) provide guides and support the type bars 118 for movement in a horizontal plane. Each of the type bars is acted on by a spring 121 (Fig. 14) extending between a spring anchor 122 on the type bar and a spring anchor 123 on the 30 rod 124 carried by the arms 125 (Fig. 6) fast to the shaft 126 journaled in the frame of the machine. An arm 125 is provided adjacent each end of the printing couple E and unitary with each of these arms is an arm 127 having a roller 128 at the free end thereof engageable with a peripheral cam 129 fast on the shaft 43. As the shaft 43 rotates, the cams 129 act on the rollers 128 to impart movement to the arms 127 and 125 so that the rod 124 will move toward the right, as 35 viewed in Fig. 6, which is toward the front of the machine. The ends of the various type bars are urged toward the rod 124 by the springs connected thereto and unless otherwise prevented the ends of these type bars engage said rod throughout the 40 movement thereof. When the rod moves toward the front of the machine, the type bars will move therewith, and when the rod attains its forwardmost position all of the type bars will be engaging the rod with the respective integers on each of 45 the type bars aligned with corresponding integers of the other of the type bars. Immediately after the rod 124 attains forwardmost position, the cam 129 so acts that the rod 124 will start to move rearwardly, and this movement is continued until 50 the rod 124 attains its rearwardmost position. A reciprocatory movement is thus imparted to the rod 124 and the type bars and the type characters on these type bars move through printing position 55 below the platen P' during this reciprocatory movement.

During said forward movement of the rod 124 the various type bars are moved into forward position to insure alignment of the integers on the respective bars. During rearward movement of 60 these type bars means operate to stop the selected type character in printing position.

Type bar latching (mutable printing mechanism)

On each of the type bars is a series of ratchet 75 teeth 130 spaced correspondingly to the spacing

of the type characters and preferably there are as many teeth 130 on each bar as there are type characters. Associated with each type bar is a pawl 131 pivotally mounted at 132 and including a tail 133 having one end of a spring 134 connected thereto, the other end of this spring being secured to a latch arm 135 pivotally mounted at 136. The spring 134 acts differentially and tends to pivot the pawl 131 upwardly and at the same time urges the latch arm toward the end of the pawl. The spring 134 acts on the pawl 131 to hold the nose 138 of the pawl in the notch 137 in the latch arm 135 to thereby hold the pawl 131 out of engagement with the teeth 130. The latch arm 135 is unitary with an arm 139 having 15 a link 140 connected thereto, which link is likewise connected to the armature 141 of an electro-magnet 142.

When the electro-magnet 142 is energized, the armature 141 is attracted and movement is imparted through the link 140 to the arm 135 to thereby so pivot the latch arm that the notch 137 is disengaged from the shoulder 138, whereupon the spring 134 pivots the pawl 131 upwardly into engagement with one of the teeth 130 to thereby interrupt further movement of the type bar so engaged to thereby position a determined of the type characters in printing position below the platen P'. The rod 124 will continue to move with the arms 125, and the spring of 30 the arrested type bar will be elongated. A pawl capable of being so operated is associated with each of the type bars and therefore any one of the type characters on these type bars may be stopped and retained in printing position by 35 causing the pawl 131 to engage the ratchet teeth at the time the desired type character is in printing position.

Type bar release

Extending between the arms 125 is a rod 124' (Fig. 6) and as the arms 125 and rod 124 move forwardly this rod 124' engages the adjustable screws 98' at the upper end of pawls 99 to thereby unlatch the armatures 92 so that the contacts 45 95 and 97 will be reengaged.

Electrical control of type bar setting

After a control device has moved through the 60 stages W', X', and Y', into the stage Z', it is in position to control the type bars 118 of the printing couple E whereby this printing couple may be arranged to print the proper variable data on a sheet which received impressions from the 65 changeable printing device that has moved from the stage W through the stages X and Y into the stage Z whereat impressions were made on the sheet from this printing device by the platen P. The control device in the stage Z', which is to 70 determine the set-up of the type bars to make impressions on the sheet next to move into the printing couple E, is the control device which was in the stage W' at the time the changeable printing device from which impressions were 75 made on the sheet was in the stage W.

In order that the proper type characters on the type bars will be stopped in printing position, the control device in the stage Z' moves past a set of detector brushes 143, carried by the insulating block 144, simultaneously with the rearward movement of the rod 124.

The lineation on the control device C is such that the integers associated therewith are in the same sequence as the sequence of the type char- 75

acters on the type bars so that perforations made at determined points in the lineation will cause a corresponding type character to be stopped in printing position.

5 It has been pointed out that a plate of conductive material underlies each of the control devices in the pockets 33. A brush contact 145 (Fig. 5) engages the plate 89 in the stage Z'. The brush contact 145 is connected to a suitable 10 source of electric current and one end of the winding of each of the electro-magnets 142 is connected to the other side of the source of current. Each of the brushes 143 may be respectively connected to one end of the winding of one 15 of the electro-magnets 142 whereby each brush 143 will control an electro-magnet 142.

It may be noted that the same brush may be connected to two or more electro-magnets when similar impressions are to be made at spaced 20 places in one of the groups, this being shown in Fig. 16, for as there illustrated some numbers are twice printed in the row J.

As the control device moves from the stage Z' past the brushes 143, circuit will be closed to 25 the various electro-magnets as the brushes 143 pass through perforations in the control device. The perforation in the control device will move into alignment with the brush 143 at the time the desired type character on the type bar associated 30 with the electro-magnet 142 controlled by this brush moves into printing position, and therefore as this brush moves through a perforation, the pawl 131 will seat in the tooth 130 aligned therewith to retain this type character in printing 35 position. In this manner the various type bars in the printing couple E will be so positioned that the type characters for printing the data in the row J will be aligned with the platen P' of the printing couple E.

40 It should be noticed that certain of the brushes 143 traverse that portion of the control device perforated to determine the account number whereby certain of the type bars 118 will be positioned to print this account number N', and 45 these type bars are so disposed that the account number printed from the type bars 118 will be printed on a section of the sheet other than that having the account number printed thereon by the receding portion of the platen P, which 50 operates with the changeable printing devices D.

The platen P' of the printing couple E descends and prints the data in the row J on the sheet and immediately thereafter the rod 124 starts to move toward the right, as viewed in Fig. 6, 55 or 9, and picks up the various type bars and moves them back into aligned relation at the forward end of the movement of the rod 124, and during the subsequent rearward movement these type bars are again positioned to print on 60 the succeeding sheet.

Printing couple F

The control device which previously positioned 65 the type bars 118 of the couple E will now move past the brushes 147 carried by the insulating block 148, and in moving past these brushes this control device will determine the position of the type bars in the printing couple F. This 70 corresponds to the printing couple E in construction and operation, whereby an impression may be made from the type characters on these type bars onto the sheet in the row K by the platen P' of said printing couple F; said sheet being stopped in printing position relative to said 75

platen P' by one of the stop fingers F' operated from the cam shaft 25.

Sheet positioning (continued)

The impressions in the row K are out of longitudinal alignment with impressions in the row J and to permit the printing of the data in these rows I arrange the printing position in the printing couple F out of longitudinal alignment with the printing position in the printing couple E and therefore the sheet may move through the machine in a straight line. However, if desired, the sheet may be moved at an angle to this straight line movement to permit the printing of the row K out of longitudinal alignment with the row J, and this may be done by providing means for jogging the sheet such as that disclosed in the application of Franklin Edwin Curtis, Serial No. 454,595, filed May 22nd, 1930, now Patent No. 1,941,663, patented January 20 2nd, 1934.

The stop fingers, which position the sheets relative to the various platens, are retracted immediately after the desired printing operations have been performed to permit the sheet to move along with the conveyor belts 26 into position relative to the next printing couple, and after the last impression has been made on the sheet by the last of the printing couples the sheet is discharged into a suitable collector. 30

Mutable printing mechanism drive (timing operation)

The mutable printing devices of the printing 35 couples E and F and the drum 34 are operated from an independent source of power consisting of the motor 38.

It is necessary that the operation of the mutable printing mechanisms be in timed relation 40 with the operation of the platen P and allied mechanisms and therefore I control the operation of the mechanisms operated by the motor 38 by a cam 38' (Fig. 8) on the cam shaft 25. The cam 38' has a shoulder 39' thereon which 45 may seat in the notch 48' in the link 41' to move this link toward the left, as viewed in Fig. 8, whereby the latch arm 42' will be turned in a counter-clockwise direction about the pivotal mounting 43' to thereby disengage the shoulder 50 44' from the lug 45'. On the arm 48' is a spring 47' normally holding the shoulder in engagement with the lug. A spring 50' extends between a spring anchor on the frame and an arm 48' pivotally mounted at 49'. When the shoulder 55 44' disengages the lug 45', the spring 50' pivots arm 48' to cause the fork 51'', riding in the grooved collar of one portion of the jaw clutch 40, to move this collar to engage said jaw clutch. The fork carries a depending lug 52'' and when 60 it is moved, as just described, an adjustment screw 53'' carried by this lug closes this switch 54' to thereby set the motor 38 in operation.

A roller 25'' on the arm 46' is spring-urged 65 into engagement with a cam 24'' on the shaft 43 and after the jaw clutch is engaged this cam allows the arm 46' to move downwardly to re-engage the lug 45' on the shoulder 44'. Further rotation of the cam then causes the parts to assume their initial positions with the clutch disengaged and the switch 54' opened. 70

Since the inertia of the motor will not be imparted to the various parts operated therefrom by reason of the disengagement of the clutch, these parts will always stop in substantially the 75

same position from which they may be again moved when the clutch is reengaged.

General operation (preparation)

5 The operation of the machine is as follows: A plurality of sheets having a permanent form printed thereon are introduced into the rack T, Fig. 1, or when a machine similar to that shown in the referred to Hartley application is to be employed, a web will be arranged so that sheets may be severed therefrom.

10 Printing devices are introduced into the magazine M and control devices, supposedly arranged in the same sequence as the printing devices, are introduced into the magazine A. The machine is then arranged so that there will be a printing device in each of the printing stages Z, Y, X and W, Fig. 2, and so that there will be a control device in each of the stages Z', Y', X', and W', Fig. 4. A sheet will be positioned on the conveyor belts 26 in engagement with the first stop finger F' farthest to the right, Fig. 1, which serves to orient the first section of the sheet relative to the platen P.

25 *Actuation*

30 The machine is now set in operation by engaging the clutch to connect the pulley 20 to the shaft 19 and the platen operating shaft will be rotated and will cause the platen P to descend to make an impression R on the first section of the sheet.

Sheet feed and positioning

35 The cam shaft 25 and the conveyor belts 26 will also be set in operation and during the time the platen P is ascending after having made the impression on the first section of the sheet a cam on the shaft 25 will retract the first stop 40 finger F' and will move the second stop finger into stopping position and as soon as the first stop finger is disengaged from the leading edge of the sheet, the sheet will be carried by the conveyor belt into engagement with the second of the 45 stop fingers to be oriented thereby relative to the platen P to receive an impression on the second section thereof. This operation will be carried out until each of the stop fingers has so oriented the sheet that an impression will be made on each 50 section thereof, whereupon the sheet will move into engagement with the stop finger F' (shown between couples E and F, Fig. 1) that orients the sheet relative to the platen P' in the printing couple E.

55 *Actuation of mutable printer and control card feed*

60 Immediately after the platen P has made the first impression on the sheet from the printing device D in stage Z the cam shaft will move the cam 38', Fig. 8, into such a position that the shoulder 39' thereon will seat in the notch 40' to set the motor 38 in operation and engage the jaw clutch 40 whereby the shaft 43 will be rotated, 65 and this movement will be transmitted through the miter gears 45 and 46 to the shaft 47 to rotate the crank discs 55.

65 The movement imparted to the crank discs 55 is transmitted through the link 54 to the rocker 51 and the initial movement of the link moves the rocker in a clockwise direction, as viewed in Fig. 4, to withdraw the pawl 52 from engagement with one of the teeth in the ratchet 50 to seat it in the succeeding tooth. Immediately after this pawl 70 is seated in this succeeding tooth, the crank discs

will have rotated into such a position that movement will be imparted to the rocker 51 in a counter-clockwise direction, and, by reason of the engagement of the pawl 52 in a tooth of the ratchet 50, the drum 34 will be rotated in a 5 counter-clockwise direction.

As the drum 34 rotates, the card in the stage W' will move past the brushes 69 and the slide 31 will be so operated that it will move the leading edge of a control device C into position below the roller 66 whereby another control device will be located in the stage W' to succeed the control device which has been in the stage W' and which now will be located in the stage X'.

10 *Detecting (identification or comparison)*

15 At the time the rocker 51 moves in a counter-clockwise direction, as viewed in Fig. 4, the frame 73 will be so moved that the brushes 71 will pass across the card 37 on the printing device in the stage W, and as the drum will be rotating at this time it is manifest that a control device C will be traversing the brushes 69 in synchronism with the traversing of the card 37 by the brushes 71.

20 *Results of comparison*

25 If the control device and the card on the printing device are performed correspondingly, circuit to the electro-magnet 103 will not be closed at the time the switch 101 is closed by the operation of the cam shaft 25. If, however, the control device and the card do not correspond, the magnet 103 will be energized at the time the switch 101 is closed and operation of the machine will be interrupted. The time switch 105 is operated 35 substantially at the time the drum 34 reaches the end of its movement in a counter-clockwise direction, which carries a card C from one stage to another.

40 *Setting mutable printers*

45 As the drum 34 rotates in the above described manner, the control card which has been in the stage Z' moves past the brushes 143 to thereby position the type bars in the printing couple E.

50 *Printing devices D; feed and printing*

55 At the time the platen P is ascending after having made the last impression R on the sheet positioned therebelow, the printing device feed mechanism will be rendered operative, and the printing device which has been in the stage Z will be moved therefrom and the printing device that has been in the stage Y will be moved into the stage Z, and the sheet will move from the printing 55 couple, including the platen P, into the printing couple E to be positioned below the platen P'.

60 *Printing at Couple E*

65 As the platen P descends to make the first impression on the sheet immediately behind that which has moved into the printing couple E, the rises on the cams 113 will engage the rollers 112 to cause the platen P' to descend, whereby the impressions in the row J will be made on the sheet. This operation of the platen P' is very rapid and immediately after the platen has ascended sufficiently to disengage the sheet the rod 124 starts to move forwardly to engage the type bars of the printing couple E, and at the time the rod 124 attains its forwardmost position and starts to move rearwardly, the rocker 51 will start to move in a counter-clockwise direction, and the drum 34 will again be rotated and the control device which moved past the brushes 143 75

during the previous movement of the drum 34 will move past the brushes 147 to position the type bars in the printing couple F. Manifestly, at this time the control device which has been in the stage Z' will move past the brushes 143 and the control device which has been in the stage W' will move past the brushes 69 to operate as previously described.

10 *Printing at couple F*

After the platen P has made the last impression on the sheet associated therewith, the last of the stop fingers F' for orienting the sheet relative to the platen P will be retracted and this sheet will move into the printing couple E, and the sheet which has been in the printing couple E will be moved with the conveyor belts 26 to engage the stop finger which positions the same relative to the platen P' of the printing couple F.

Simultaneous printing (on D and at E and F)

At the time the platen P is descending to make an impression R on the sheet now disposed in position therebelow, the platens P' of the printing couples E and F will descend to make impressions on the sheets positioned therebelow, the platen P' of the printing couple F making the impression in the row K on the sheet which 30 previously received impressions in the row J in the printing couple E.

If there are additional printing couples in the machine, the sheet just receiving impressions in the row K will move into the succeeding printing couple on the next cycle of operation of the machine, and the sheets will so move through successive printing couples until all the desired impressions will have been made thereon whereupon the sheets will pass from the machine into 40 a suitable collector.

Printed comparison index, etc.

The sheets receive impressions R on each section thereof during movement through the machine and in addition the account number N is printed from the changeable printing devices at a desired place or places on the sheets. This account number is also printed on the sheets in one of the printing couples embodying mutable 50 printing devices, whereby it may be easily ascertained from the printed sheets whether or not the variable data printed thereon is that which should be associated with the impressions R. This facilitates checking of the sheets but it is 55 apparent that discrepancy between the variable data and the impressions R is unlikely by reason of the detection afforded by the detecting means including the brushes 69 and 71 which determine, in the machine, whether or not corresponding printing devices and control devices are located relative to each other. Moreover, the sheets may be completely printed during passage thereof through the machine for not only names and addresses may be printed thereon 60 but mutable printing devices may be employed to print quantities, prices, and extensions thereof, or any other desired data. Thus, completely printed sheets will be delivered into the collector at the discharge end of the machine.

70 It is to be understood that the mutable printing device may be employed to print any desired information, and while I have shown the type bearing elements of these printing devices as having numerals thereon, the letters of the alphabet or any other desired printing characters may

be provided. Furthermore, the machine may be used to print sheets having one, two or any number of sections.

While I have illustrated and described a selected embodiment of my invention it is to be understood that this is capable of variation and modification and I therefore do not wish to be limited to the precise details set forth, but desire to avail myself of such changes and alterations as fall within the spirit and scope of the following 10 claims.

I claim:

1. In a printing machine, printing means for making an impression on a sheet, a mutable printing mechanism for making another impression on the sheet, feed tapes for moving a sheet through said printing means and said printing mechanism, and means operable with the printing means for timing the operation of the printing mechanism.

2. In a printing machine, means supporting a supply of sheets, printing means for making impressions on said sheets, a printing mechanism for making impressions on said sheets related to the first impressions, means for withdrawing said sheets from the supply, continuously operating means for receiving sheets from said supply and for moving said sheets through said printing means and said printing mechanism, means for interrupting movement of said sheets with said 20 continuously operating means during the operation of said printing means and said printing mechanism, and means operable with the printing means for timing the operation of the printing mechanism and the interrupting means.

3. In a printing machine through which sheets are passed, printing means for making impressions on said sheets from changeable printing devices, a mutable printing mechanism for making impressions on said sheets, constantly operating means for moving said sheets through said printing means and said printing mechanism, means for interrupting movement of said sheets during the impression operations of said printing means and said printing mechanism, and means operable with the printing means to time the operation of the printing mechanism to thereby effect operation of the printing mechanism in fixed timed relation with the changing of said changeable printing devices.

4. In a printing machine through which sheets are passed, printing means for making impressions on said sheets from changeable printing devices, a mutable printing mechanism for making impressions on said sheets, means for checking the operation of said mutable printing mechanism against the operation of said printing means whereby impressions are made on said sheets by said mutable printing mechanism which are related to the impressions made on said sheets from the respective changeable printing devices by said printing means, continuously operating feed tapes for moving said sheets through said printing means and said printing mechanism, means for interrupting movement of said sheets during the impression operations of said printing means and said printing mechanism without interrupting operation of said feed tapes, and means operable with the printing means to time the operation of the checking and interrupting means and the 50 printing mechanism.

5. In a printing machine, printing means for making an impression on a sheet, operating means for said printing means, a mutable printing mechanism, operating means for said mutable 75

- printing mechanism, means moving the sheet through said printing means and said printing mechanism, means for positioning the sheet in the printing means, means for positioning the sheet in the printing mechanism, and means operated by one of said operating means for timing the operation of the other operating means and the respective positioning means.
6. In a printing machine, printing means for making an impression on a sheet, operating means for said printing means, a mutable printing mechanism, means for arranging said mutable printing mechanism to make an impression on the sheets related to the impression made thereon from said printing means, operating means for said mutable printing mechanism and the means arranging said mutable printing mechanism, means for moving the sheet through said printing means and said printing mechanism, means for positioning the sheet in the printing means, means for positioning the sheet in the printing mechanism, and means operated by the operating means for the printing means for timing the operation of the respective positioning means and the means operating said mutable printing mechanism.
7. In a printing machine, means for moving a series of changeable printing devices through a series of stages in the machine, a platen for making impressions from said changeable printing devices on sheets moved through the machine, a mutable printing mechanism, means for moving a series of control devices through a series of stages in the machine corresponding to the first series of stages whereby there is a control device in each of the stages therefor corresponding to a changeable printing device in each of the stages therefor, means controlled by said control devices for arranging said mutable printing mechanism to make impressions on the sheets related to the impressions made thereon from said changeable printing devices, continuously operating means for moving the sheets through said printing means and said printing mechanism, and means for orienting the sheets to receive impressions successively in said printing means and said printing mechanism.
8. In a printing machine, printing means for making an impression on a sheet, operating means for said printing means, a mutable printing mechanism, operating means for said mutable printing mechanism, continuously operating feed tapes for moving a sheet successively through said printing means and said printing mechanism, means for interrupting the movement of the sheet with said feed tapes to position the sheet in the printing means to receive an impression therein, means for interrupting the movement of the sheet with the feed tapes to position the sheet in the printing mechanism to receive an impression therein, and means operated by the operating means for the printing means to successively operate the means positioning the sheet in the printing means and the means positioning the sheet in the printing mechanism and to time the operation of the operating means for said mutable printing mechanism.
9. In a printing machine through which sectional sheets are passed, constantly operating means for moving the sheets through the machine, printing means for making independent impressions on each section of said sheets, means for interrupting movement of the sheets to successively position the sections thereof to receive impressions from said printing means, a mutable printing mechanism for simultaneously making impressions on the sections of each sheet, means for interrupting movement of the sheets during the impression operation of said printing mechanism, common means for controlling the operation of said interrupting means, and means operable with the printing means to time the operation of the interrupting means and the printing mechanism.
10. In a printing machine, printing means for making an impression on a sectional sheet, operating means for said printing means, a mutable printing mechanism, operating means for said mutable printing mechanism, constantly operating feed tapes for moving the sheet through said printing means and said printing mechanism, means for interrupting the movement of the sheet with the feed tapes to successively position the sections of the sheet in the printing means to receive an impression therein, means for interrupting movement of the sheet with the feed tapes to position the sheet in the mutable printing mechanism to receive an impression in the mutable printing mechanism on the sections thereof simultaneously, and means operated by the operating means for the printing means to time the operation of the interrupting means and the means operating the mutable printing mechanism.
11. In a printing machine, printing means for making an impression on a sheet, operating means for said printing means, a mutable printing mechanism, another mutable printing mechanism, operating means for said mutable printing mechanisms, means moving the sheet through said printing means and said printing mechanisms, means for positioning the sheet in the printing means, means for positioning the sheet in the first mutable printing mechanism, means for positioning the sheet in the other mutable printing mechanism, and means operated by one of said operating means for timing the operation of the other operating means and the respective positioning means.
12. In a printing machine, means for moving changeable printing devices through a series of stages of which one is a printing position in the machine, a platen for making impressions from said printing devices onto sheets moved through the machine when said devices are moved into the printing position, a mutable printing mechanism, control means movable into a position whereat the control means arranges said mutable printing mechanism to make impressions on the sheets, and means for moving said control means through a series of stages corresponding in number to the series of stages through which the changeable printing devices are moved.
13. In a printing machine, means for moving changeable printing devices through a series of stages of which one is a printing position in the machine, a platen for making impressions from said printing devices onto sheets moved through the machine when said devices are moved into the printing position, a mutable printing mechanism, control means movable into a position whereat the control means arranges said mutable printing mechanism to make impressions on the sheets, means for moving said control means through a series of stages corresponding in number to the series of stages through which the changeable printing devices are moved, and means for determining the relationship of the printing devices and the control means moving through said stages prior to the movement of a

printing device into the printing position and movement of the control means into said position whereat the control means arranges said mutable printing mechanism.

5 14. In a printing machine, two printing mechanisms, one including settable printing devices, the other being adapted to print from individual printing devices fed seriatim to printing position, an ordered series of control devices for the 10 settable printing devices, means cooperating therewith to arrange the settable printing devices for printing operations, an ordered series of control members associated with the respective individual printing devices, said control members being supposedly in the same order as the 15 control devices, and detecting means operated by the machine prior to printing to determine whether the control devices and members are in proper order.

20 15. In a printing machine, means for moving individual printing devices and respectively related control devices, each in a supposedly ordered series, through successive stages wherein individual supposedly corresponding devices of 25 each series successively occupy respective identifying positions, detecting means acting on the respective devices in their identifying positions to determine if the devices operatively correspond, and printing means disassociated from 30 said printing devices, said printing means being rendered operative by said control devices which are found by the detecting means to correspond with a printing device in the detecting positions of said devices.

35 16. In a printing machine, a settable printing mechanism and a set of ordered control members therefor adapted to set the same for printing, a second printing mechanism adapted to print from individual printing members, a supposedly corresponding set of ordered control 40 members for the second printing mechanism, and detecting means operated by one of said mechanisms and cooperating successively with respective members of both sets of control members 45 to determine whether said members are in proper order, prior to the functioning of either printing mechanism to print.

17. In a printing machine, means for moving changeable printing devices through successive 50 stages in the machine whereby impressions may be made from a printing device in a predetermined stage, a mutable printing mechanism, and control devices movable in timed relation with the printing devices through stages corresponding to the stages for said changeable printing devices and adapted to arrange said mutable printing mechanism to make impressions on the sheet receiving impressions from the changeable printing device in said predetermined stage, there being a control device for each of said changeable 55 printing devices.

18. In a printing machine, means for moving changeable printing devices through successive stages in the machine whereby impressions may 60 be made on a sheet from a printing device in a predetermined stage, a mutable printing mechanism, control devices for arranging said mutable printing mechanism to make impressions on the sheet receiving impressions from the changeable printing device in said predetermined stage, means for moving said control devices in timed relation with the printing devices through successive stages corresponding to the stages through which said changeable printing devices 65 are moved, there being a control device for each

changeable printing device, constantly operating means for moving the sheet through said printing means and said printing mechanism, and means for interrupting movement of the sheet during operation of the printing means and printing mechanism.

5 19. In a printing machine, means for moving changeable printing devices through successive stages in the machine whereby impressions may be made from a printing device in a predetermined stage on a sheet, a mutable printing mechanism, control devices for arranging said mutable printing mechanism to make impressions on the sheet receiving impressions from the changeable printing device in said predetermined stage, means for moving said control devices through successive stages corresponding to the stages through which said changeable printing devices are moved, the moving means for said printing devices and said control devices operating in timed relation so that the printing devices and control devices move through the stages therefor in timed relation with each other, there being a control device for each printing device, and means for determining the relation 20 between said printing devices and said control devices whereby a control device in one of the stages through which said control devices are moved will correspond to a printing device in a predetermined one of the stages through which said 25 printing devices are moved.

20. In a printing machine, means for moving changeable printing devices through successive stages in the machine whereby impressions may be made from a printing device in a predetermined stage on a sheet, a mutable printing mechanism, control devices for arranging said mutable printing mechanism to make impressions on the sheet receiving impressions from the changeable printing device in said predetermined stage, means for moving said control devices through successive stages corresponding to the stages through which said changeable printing devices are moved, the moving means for said printing devices and said control devices operating in timed relation so that the printing devices and control devices move through the stages therefor in timed relation with each other, there being a control device for each printing device, means for determining the relation between said 30 printing devices and said control devices whereby a control device in one of the stages through which said control devices are moved will correspond to a printing device in a predetermined one of the stages through which said 35 printing devices are moved.

10 21. In a printing machine, means for moving changeable printing devices through a series of stages of which one is a printing position in the machine, a platen for making impressions from said printing devices onto sheets moved through the machine when said devices are moved into 40 the printing position, a mutable printing mechanism, control devices respectively related to the printing devices movable into a position whereat each control device arranges said mutable printing mechanism to make an impression on the sheets, means for moving said control devices through a series of stages corresponding in number to the series of stages through which the changeable printing devices are moved, and means for determining the relationship of the 45

- printing devices and the control devices moving through said stages prior to movement of a printing device into printing position and movement of a control device into the position whereat the 5 control device arranges said mutable printing mechanism, whereby said mutable printing mechanism will make an impression on a sheet related to the impression from the printing device related to the control device arranging said mutable printing mechanism.
22. In a printing machine, printing means for making an impression on a sheet from one of a series of changeable printing devices, means for moving the printing devices through a series of 10 stages in the machine in a step by step manner, a mutable printing mechanism for making an impression on said sheet, control devices adapted to arrange the mutable printing mechanism to make a predetermined impression on the sheet, 15 common means moving the sheet through said printing means and said printing mechanism, and means moving the control devices through a series of stages through which the changeable printing devices are moved in a step by step manner, 20 there being a control device for each printing device, the changeable printing devices and control devices moving in timed relation with each other to maintain the paired relation of said printing devices and said control devices.
23. In a printing machine including printing means embodying changeable printing devices and a mutable printing mechanism adapted to be arranged by control devices, means for moving 25 changeable printing devices through a series of stages in the machine, means for moving control devices through a series of stages in the machine corresponding in number to the series of stages through which the changeable printing devices are moved, there being a control device for each 30 printing device, identifying means on the printing devices, identifying means on the control devices, and means including detecting portions located at predetermined of said stages and cooperating with the identifying means on the 35 printing devices and control devices for determining the relationship between the printing devices and the control devices.
24. In a printing machine including printing means embodying changeable printing devices and a mutable printing mechanism adapted to be arranged by control devices, means for moving 40 changeable printing devices through a series of stages in the machine, means for moving control devices through a series of stages in the machine corresponding in number to the series of stages through which the changeable printing devices are moved, there being a control device for each 45 printing device, identifying means on the printing devices, identifying means on the control devices, detecting portions located at predetermined of said stages and cooperating with the identifying means on the printing devices, and means cooperating with said detecting portions for interrupting operation of the machine 50 in event the identifying means on the printing device engaged by the detecting portions cooperating therewith does not correspond with the identifying means on the control device engaged by the detecting portions cooperating therewith.
25. In a printing machine including printing means embodying changeable printing devices and a mutable printing mechanism adapted to be arranged by control devices, means moving 55 changeable printing devices through a series of stages in the machine, means moving control de-

vices through a series of stages in the machine corresponding in number to the series of stages through which the changeable printing devices are moved, there being a control device for each printing device, removable identifying means on the printing devices, said control devices including identifying means relating to the identifying means on the printing devices, and means located at predetermined of said stages and cooperating with the identifying means to determine the relation between said printing devices and control devices whereby a control device related to a printing device will arrange a mutable printing mechanism to make an impression on a sheet receiving an impression from the changeable printing device related to said control device.

26. In a printing machine including printing means embodying changeable printing devices and a mutable printing mechanism adapted to be arranged by control devices, means moving 20 changeable printing devices through a series of stages in the machine, means moving control devices through a series of stages in the machine corresponding in number to the series of stages through which the changeable printing devices are moved, there being a control device for each printing device, removable identifying means on the printing devices, said control devices including identifying means related to the identifying means on the printing devices, means located at predetermined of said stages and cooperating with the identifying means on the printing devices and the identifying means on the control devices for determining the relationship therebetween, and means for interrupting operation of the machine in event the identifying means on the printing device does not correspond with the identifying means on the control device whereby the machine will continue to operate when said identifying means correspond so that 30 the mutable printing mechanism is arranged to make an impression on a sheet receiving an impression from the changeable printing device related to said control device.

27. In a printing machine having means for 45 making impressions on sheets moved therethrough, a mutable printing mechanism, control devices for arranging said mutable printing mechanism to make impressions on said sheets related to the impressions made thereon by said printing means, means for operating said printing means, independent means for operating said mutable printing mechanism, and means for said printing means for controlling operation of the independent means operating said mutable printing mechanism.

28. A mutable printing mechanism including a plurality of type carriers, means for determining the position of said type carriers whereby predetermined printing characters thereon will 50 be disposed in printing position, said means including a member movable in synchronism with the movement of said type carriers, control devices for determining the positioning of said type carriers, and means for positioning said control devices on said member whereby said control devices will also be moved in synchronism with the movement of said type carriers.

29. A mutable printing mechanism including a plurality of type carriers, a drum, means for 70 imparting synchronic movement to said type carriers and said drum, and means for positioning control devices for said type carriers on said drum for movement therewith whereby a control device at a predetermined position on said drum may 75

determine the positioning of said type carriers relative to a printing member cooperating with said mutable printing mechanism.

30. A mutable printing mechanism including a plurality of type bars adapted to have printing characters thereon selectively located in a printing position, a movable support, means for imparting synchronous movement to said type bars and support, and means operating in timed relation with said support for positioning control devices thereon whereby a control device in a predetermined position may serve to determine the locating of printing characters on said type bars in printing position.

15 31. A mutable printing mechanism including a plurality of type bars adapted to have printing characters thereon selectively located in a printing position, a drum, means for imparting synchronous movement to said type bars and said drum, means operating in timed relation to said drum for positioning control devices thereon, and means regulated by control devices disposed in predetermined positions on said drum for locating printing characters on said type bars in printing position.

32. In a printing machine through which interrelated printing devices and control devices are moved, means for determining the interrelation of said printing devices and said control devices including an electric circuit, means normally holding said electric circuit in operative condition, means for opening said electric circuit when interrelated printing devices and control devices move into predetermined positions in said machine, separate means included in said electric circuit for traversing the printing devices and control devices, and common means for operating the separate means traversing said printing devices and control devices.

40 33. In a printing machine through which interrelated printing devices and control devices are moved, means for determining the interrelation of said printing devices and said control devices and including an electric circuit, means normally holding said electric circuit in operative condition, means for opening said electric circuit when interrelated printing devices and control devices move into predetermined positions in said machine, means for closing said circuit at a predetermined time in the operation of said machine, separate means included in said electric circuit for traversing the printing devices and control devices, and common means for operating the separate means traversing said printing devices and said control devices.

45 34. The combination of two series of devices, the devices in each series being supposedly arranged in the same predetermined order, corresponding indicia on the corresponding members of the two series, normally active means for feeding both series, and means to render the feeding means idle, said last-named means being actuated consequent upon the simultaneous presence in an identifying position of devices having non-corresponding indicia.

50 35. A series of members supposedly arranged in a predetermined order, a series of related printing devices supposedly arranged in the same predetermined order, the related devices and members both supposedly bearing corresponding indicia, means to feed the members into an identifying position, means to feed the devices into an identifying position, and means rendered active consequent upon the presence of a member and a device in their respective identifying posi-

tions bearing non-corresponding indicia to stop the feeding movement of the members and devices.

5 36. A series of cards supposedly arranged in a predetermined order, a series of related printing devices supposedly arranged in the same predetermined order, the devices and cards both supposedly bearing corresponding indicia, means controlled by the indicia on both the cards and devices to feed the cards from an identifying position, and means acting consequent upon the presence of the first card and device in their respective identifying positions and bearing non-corresponding indicia to prevent either of said feeding means from functioning.

10 37. In a machine through which supposedly interrelated printing devices and control devices are moved, in step with each other, means for determining the relation or non-relation of given printing and control devices, said means including an electric circuit and means for rendering the circuit active to determine the operative identity of said printing devices and control devices when the same are moved in predetermined respective positions in said machine, and means to stop the machine, said last-named means being rendered active by said circuit consequent whenever non-interrelated devices occupy said respective positions.

15 38. In mechanism of the class described, a series of individual printing devices, feeding and printing mechanism therefor, a series of control devices supposedly corresponding in order and identity to the individual printing devices, separate means for feeding the control devices, means 30 acting in advance of a printing operation of said printing mechanism to determine whether or not the device to be printed from corresponds to the control device supposed to correspond therewith, and means controlled by the determining means 35 to prevent a printing operation from taking place, and to stop the feed of both the control and printing device whenever a control device and a supposedly corresponding printing device do not correspond.

20 39. The combination of two series of devices, the devices in each series being supposedly arranged in the same predetermined order, corresponding indicia on the corresponding members of the two series, means to feed the members of 50 both series one at a time, and means actuated upon a disagreement of the indicia to stop the feeding operation of both series.

25 40. The method of maintaining a series of individual address printing plates and a series of 55 corresponding control cards in the same sequence, comprising providing each plate with a different index, providing each correlated control card with a corresponding index, feeding the plates and cards simultaneously each one at a time, comparing the index on the cards with the index of the plates as fed, stopping the feeding of both cards and plates if any such indices do not correspond, and correcting the sequence and subsequently continuing the feeding after such correction has been made.

30 41. The method of maintaining a series of individual address printing plates in proper sequence, comprising providing each plate with a different index, providing a series of individual 70 control cards each with an index corresponding to the index of its correlated address printing plate, arranging the cards in the order in which the printing plates supposedly are and in which order the plates are to be maintained, feeding 75

the plates and cards simultaneously each one at a time, comparing the index on the cards with the index of the plates as fed, stopping the feeding of both cards and plates if any such indices do not correspond, correcting the sequence and subsequently continuing the feeding after such correction has been made.

42. The method of maintaining a series of individual address printing devices and a series of corresponding control devices in the same sequence, comprising providing each printing de-

vice with a different index, providing each correlated control device with a corresponding index, feeding the devices in the two series simultaneously one at a time, comparing the index on the control devices with the index on the printing devices, stopping the feeding of both sets of devices if any such indices do not correspond, and performing a useful operation by one series of said devices during the feeding action if the devices in the two series do correspond. 5 10
